UNITED STATES PATENT OFFICE

156,939

STOCKING

Guido Clauss, Elizabethtown, Pa.

Application March 23, 1949, Serial No. 1,569

Term of patent 14 years

(Cl. D47—7)

To all whom it may concern:

Be it known that I, Guido Clauss, a citizen of the United States, residing at Elizabethtown, Lancaster County, Pennsylvania, have invented a new, original, and ornamental Design for a Stocking, of which the following is a specification, reference being had to the accompanying drawing, forming a part thereof.

Fig. 1 is a view in perspective of the stocking showing my new design;

Fig. 2 is an enlarged side elevational view of the foot portion of the stocking showing the design in detail; and

Fig. 3 is a fragmentary rear elevation as viewed from the line 3—3, Fig. 2.

I claim:

The ornamental design for a stocking, as shown.
GUIDO CLAUSS.
